EAR PROTECTING DEVICE

Boris Berkman, Chicago, Ill.

Application August 1, 1952, Serial No. 302,033

8 Claims. (Cl. 128—152)

The present invention relates to an ear protecting device and in particular to a novel device for protecting the eardrum and other inner ear parts against pain or injury caused by noises, concussion, shocks and sensible changes in the barometric pressure.

The human eardrum is located in the middle ear and responds to fluctuations in air pressure and sound waves through the auditory canal. The middle ear is connected by the Eustachian tube to the oral cavity so that pressures on the opposite sides of the drum head are normally equalized to prevent pain and injury thereto. The Eustachian tube is a normally closed slit which opens in the act of swallowing or yawning from the action of the muscles lifting the palate. This tube is readily subject to inflammation arising from colds, sinusitis and other disorders of the oral and nasal passages. Consequently, during these times of inflammation its function is impaired, and sound waves and the like impinging against the drum head will be more sharply felt, sometimes resulting in severe pain and injury.

Furthermore, a perfectly healthy person is liable to injury of his eardrums from noises of excessive type, explosions, concussions, etc., and experience has shown that it is not unusual for military personnel to suffer punctured eardrums as a result of artillery fire and explosion. In fact it is quite customary for these men to have impaired hearing for a short time after coming out of an area wherein there has been a large amount of gunfire, explosions and the like, such as a battle area or the artillery and rifle range.

It is also a known fact that air waves above the normal audible range, which varies according to the individual but generally extends between 50 and 15,000 C. P. S., are apt to cause very severe pain and permanent damage to a person's ear. These waves, because they are not audible, are exceedingly dangerous and one is not aware of their existence until a painful sensation is detected, at which time the damage more likely than not has been done.

A number of devices to prevent injury to the ear or to muffle sound have been proposed. Most, if not all, of these prior art devices have been unsuccessful for a variety of reasons. Many of them are cosmetically unattractive and people are reluctant to wear them. This is particularly true of that type of ear protector which either covers the whole ear or projects outwardly from the ear.

Many of the prior art devices are of the type which project a substantial distance into the auditory canal. Frequently the success of such device depends upon the tightness with which it plugs the auditory canal. If it is sufficiently loose to be comfortable, the normal jaw action accompanying mastication, yawning, or even conversation will be enough to cause the plug to pop out of position. Furthermore, if the fit is so snug that it resists the popping out tendency, it is apt to cause serious injury to the auditory canal and develop an infectious condi-

2

tion spreading to the eardrum and thus defeat its own purpose.

Some of the prior art devices include solid fiber material, such as cotton, wool, silk, and synthetic fibers, as a sound insulating means. At times these fibers have been impregnated with paraffin or the like. Tests have conclusively demonstrated that such fibers are inadequate in muffling sound waves and at high frequencies—4000 C. P. S. to 8000 C. P. S.—show very little suppression characteristics.

Experiments have conclusively shown that it is not essential that the ear protector be inserted into the auditory canal but merely that it close and provide an adequate block at the outer end of the auditory canal. Furthermore, experiments have also shown that, when the ear protector is made in a large part of a cellular fibrous material, an extremely effective block of high frequency sound waves and air waves beyond the audible range is obtained, while also permitting muffled but adequately audible transmission of sound waves within the conversational range lying between 500 and 2000 C. P. S.

It is the principal object of the present invention to provide a device for preventing pain and injury to the ear, particularly the eardrum, arising from noises, concussions, shocks, explosions and excessive and sensible changes in the barometric pressure at opposite sides of the drumhead.

It is another object to provide a novel ear protecting device adapted to be held in air wave blocking position at the outer end of the auditory canal with perfect comfort and cosmetic attractiveness.

Another object is to provide a novel ear protecting device which will substantially block and muffle sound waves of high frequency and air waves of a frequency higher than the audible range so as to prevent pain and injury to the ear, and which also will permit sounds in the conversational range to reach the eardrum.

A further object is to provide a novel ear protecting device which may be worn with perfect comfort and which will also stay in place during those movements of the jaw required by mastication and yawning and which will not be dislodged by a violent movement of the body or the head or a blow on the ear.

Another object is to provide a novel ear protecting device which is readily put in sound-blocking position at the outer end of the auditory canal and removed from that position.

Another object is to provide a novel ear protecting device in which a quantity of fine air cell providing material is held in sound and air wave blocking position at the outer end of the auditory canal.

Still another object is to provide a novel ear protecting device attaining all of the foregoing objectives and which is economical to manufacture, easily packaged, and may readily be carried in one's pocket or purse.

Other objects and advantages will become apparent from the following description taken in conjunction with the accompanying drawing, wherein:

Fig. 1 is a fragmentary view of a human head and ear showing the novel ear protecting device of this invention in sound and air wave blocking position at the outer end of the auditory canal;

Fig. 2 is a view similar to Fig. 1 but illustrating the manner in which the ear protecting device is manipulated to place it in position or to remove it;

Fig. 3 is a sectional view through the auditory canal and illustrates the manner in which the ear protecting device of this invention closes the outer end of the canal;

Fig. 4 is a longitudinal cross sectional view of a preferred form of ear protecting device constructed according to this invention;

Fig. 5 is a view similar to Fig. 4 but illustrating a modified form of ear protecting device; and

Fig. 6 is an end view of the device and may be considered as being taken from the right end of Fig. 4.

During the following description reference will be had to different portions of the human ear, and the following table designates the reference characters for the different parts of the ear:

- A—helix
- B—antihelix
- C—fossa of the antihelix
- D—antitragus
- E—tragus
- F—concha
- G—auditory canal

Referring first to the principal modification, and in particular to Fig. 4, the ear protecting device is indicated as a whole by the reference character 10 and comprises a central tubular part 12 terminating at one end in a bulb-like or bulbular casing 14. Its opposite end 16 is closed by a removable plug 18. The tubular part 12 and bulbular casing 14 are preferably made of a very high quality rubber or latex, and it has been found that the wall of the tube might properly be about $\frac{3}{16}$ " or $\frac{1}{16}$ " thick, and the outside diameter be not greater than $\frac{1}{4}$ ". If the tubular portion be about $\frac{3}{4}$ " long, a satisfactory length is provided for the device 10 so that it might fit the average human ear. The diameter of the bulbular casing 14 is between $\frac{1}{2}$ " and $\frac{5}{8}$ " with a wall thickness about $\frac{1}{32}$ " so that the casing is sufficiently pliable comfortably to fit the wearer's ear and effectively to conform itself to the outer end of the auditory canal.

The casing 14 is filled with an air cell providing material 20 which is inserted through the tube 12 in a suitable manner such as by dilating the tube and holding it in dilated position until the casing 14 has been filled. The cellular material 20 preferably may consist of milkweed floss fibers, kapok fibers or cellular glass fiber. Experience has shown that milkweed floss fiber is preferred over other known cellular fibers because of its deterioration resisting characteristics, its ease in handling, and its somewhat lighter weight. Milkweed floss in its natural state is an extremely fine tube having a length of $\frac{3}{4}$ " to $1\frac{1}{2}$ " and in its separated form is closed at one end and open at the other end to form a minute dead air space or cell. Milkweed floss fiber, or other air cell providing fibers filling the casing, provide within their fiber structure a very great multiplicity of extremely small air cells, and another multiplicity of small air spaces or traps is provided among these fibers. Sound blocking characteristics of the cellular fibrous material in the casing 14 arise from the combination of the dead air spaces in the fibers and the minute traps of the encased fibers.

It has been found, as a matter of fact, that the casing 14, filled with cellular material such as milkweed floss and placed in sound blocking position over the outer end of the auditory canal, blocks sound and air waves from entry because the casing 14 is pliable and will conform itself to the ear contour. It has been found that, with the canal so sealed, sounds or speech within the conversation range between 500 and 2000 C. P. S. are transmitted to the eardrum in sufficient intensity as to permit conversation. It is true, however, that these sounds will be somewhat muffled but not so as to prevent conversation. It has also been found that sounds in the frequency range and air waves of frequency above the audible range are very substantially muffled so that extremely sharp sounds, such as explosions, are not transmitted to the eardrum with an intensity sufficient to damage the eardrum or cause injury to the wearer. Furthermore, the ear protector affords protection against those high frequency air waves (above the audible range) which, because of their silence, are extremely insidious

in their nature and even more harmful than high frequency sound.

Experiments conducted with an ear protecting device constructed in accordance with the teachings of this invention and using milkweed floss as the sound insulating material and a prior art protector incorporating cotton fibers which were subjected to comparative tests conclusively show that the device of this invention suppresses sound in the high frequency range by as much as 35 decibels while the prior art device had suppression characteristics in the same frequency range of not more than 15 decibels.

The principles which apply to sound and air waves in connection with injury to the ear and the utility of the device of this invention in protecting against that injury likewise pertain to sensible changes in the barometric pressure. Therefore, the ear protector of this invention guards against discomfort and ear injury arising from changes in barometric pressure such for example as those encountered in air flight and ascending or descending several thousand feet in an aircraft of the nonpressurized type.

The plug 18, which closes the end 16 of the tube 12, comprises a cylindrical part 22 which is inserted into the tube 12 and a cap part 24 which has an underside 26 bearing against the outer end of the tube 12. The cap 24 has the shape generally seen in Fig. 6 and its dimension is greater in one direction than in the other being provided with substantially flat straight sides 28. The plug 18 is preferably made of rubber or a rubber-like material, and the outer surface 29 of the cap portion 26 is curved and is pliable so that it might conform itself to the shape of the concha F whereby the ear protecting device 10 is comfortably held in place.

The ear protecting device 10 is put into the sound blocking position in the ear by placing the casing 14 at the outer end of the auditory canal G and behind the tragus E. In order to then engage the cap or pad 24 in the concha F it is necessary to bend the tube portion 12 slightly outwardly to permit the cap or pad 24 to be inserted under the cartilage defining the concha F. The device is maintained in sound and air wave blocking position by virtue of the resiliency of the tubular portion 12 and the ability of the cap or pad 24 to conform itself to the shape of the concha. Because the casing 14 is extremely thin and very pliable, and because the cellular fibers 20 respond to the deformation of the casing 14, the outer end of the auditory canal G is effectively blocked by conformation of the casing to the ear configuration at the outer end of the canal. The device is removed in the same way as it was inserted, namely, by bending the tubular portion 12 outwardly and then removing the bulbular casing 14 from the outer end of the canal G and behind the tragus E.

It is observed from Fig. 1 that the device 10 occupies a very inconspicuous position in the ear, and if the tubular portion 12, casing 14 and cap 24 are tinted with a flesh color it will be substantially indetectable to the casual observer.

In the modified form shown in Fig. 5, a tube 30, having the length, diameter and wall thickness generally called for for the tubular portion 12, is provided. One end of the tube is closed by a cap or pad 32 having a plug portion 34 inserted into the tube and a hollow cap portion 36 with a curved concha engaging face 37. Because the cap portion 36 is hollow, it will shape itself into the concha F extremely readily. The opposite end of the tube 30 receives a sack 38 formed of cloth, preferably batiste, although other suitable cloth material having sterile characteristics may be used. The sack 38 is filled with cellular material—such as milkweed floss fibers, kapok fibers and cellular glass fibers—and its open end is gathered together as at 40 and inserted into the tube 30. The ear protecting device as shown in Fig. 5 is inserted into the ear and held in place in the same manner

as that shown in Fig. 4 and operates in substantially the same manner.

While preferred embodiments of the protecting device constituting this invention have been shown and described, it will be apparent that numerous further modifications and variations thereof may be made without departing from the underlying principles of the invention. It is, therefore, desired by the following claims to include within the scope of the invention all such variations and modifications by which substantially the results of this invention may be obtained through the use of substantially the same or equivalent means.

What is claimed as new and desired to be secured by United States Letters Patent is:

1. An ear protecting device of the class described comprising a quantity of air cell providing sound insulating fibers consisting of milkweed floss fiber, and means confining said fibers so as to be held in air wave blocking position at the outer end of the auditory canal.

2. An ear protecting device of the class described comprising means forming a pliable sack, a quantity of air cell providing sound insulating fibers consisting of milkweed floss fiber filling said sack, said fibers having the characteristics of substantially blocking sound and air waves of high frequency while permitting muffled transmission of such waves in the conversational frequency range, and means connected to said sack for removably securing said sack in air wave blocking position at the outer end of the auditory canal.

3. An ear protecting device of the class described comprising a pliable casing, a quantity of air cell providing sound insulating fibers filling said casing and having the characteristics of substantially blocking sound and air waves of high frequency while permitting muffled transmission of such waves in the conversational frequency range, and resilient means including a tube having an end connected to said casing and another end adapted to engage an external part of the human ear for removably holding said fiber filled casing in air wave blocking position at the outer end of the auditory canal.

4. An ear protecting device of the class described comprising a pliable casing, a quantity of air cell providing sound insulating fibers filling said casing and having the characteristics of substantially blocking sound and air waves of high frequency while permitting muffled transmission of such waves in the conversational frequency range, a bendable tube connected at one end to said casing, and a soft cap closing the other end of said tube and adapted comfortably to engage the concha of a human ear, whereby the device may be removably held in place with said fiber filled casing in sound blocking position at the outer end of the auditory canal.

5. An ear protecting device of the class described comprising a deformable bulbular casing formed of a thin rubber-like material, a quantity of air cell providing sound insulating fibers filling said casing and having the characteristics of substantially blocking sound and air waves of

high frequency while permitting muffled transmission of such waves in the conversational frequency range, a bendable tube having one end integral with said casing, said tube having a wall thickness such that said tube returns to its original shape after being released from a bending force, and soft cap means closing that end of said tube opposite said casing and adapted comfortably to engage the concha of a human ear whereby the device may be removably held in place with said fiber filled casing in sound blocking position at the outer end of the auditory canal.

6. An ear protecting device of the class described comprising a deformable casing formed of a cloth-like material, a quantity of air cell providing sound insulating fibers filling said casing and having the characteristics of substantially blocking sound and air waves of high frequency while permitting muffled transmission of such waves in the conversational frequency range, a bendable tube to one end of which said casing is secured, said tube having a wall thickness such that said tube returns to its original shape after being released from a bending force, and a soft cap means closing that end of said tube opposite said casing and adapted comfortably to engage the concha of a human ear whereby the device may be removably held in place with said fiber filled casing in sound blocking position at the outer end of the auditory canal.

7. An ear protecting device of the class described comprising a deformable thin-walled casing, a quantity of air cell providing sound insulating fibers filling said casing and having the characteristics of substantially blocking sound and air waves of high frequency while permitting muffled transmission of such waves in the conversational frequency range, a pad means adapted to engage against an external part of the human ear, and a resilient member interconnecting said casing and said pad means so that the device may be removably held in place with said fiber filled casing in sound blocking position at the outer end of the auditory canal.

8. An ear protecting device of the class described comprising a deformable thin-walled casing, a quantity of air cell providing sound insulating fibers filling said casing and having the characteristics of substantially blocking sound and air waves of high frequency while permitting muffled transmission of such waves in the conversational frequency range, and resilient means connected to said casing and including a soft pad part adapted to engage an external part of the ear for removably holding said fiber filled casing in sound blocking position at the outer end of the auditory canal.
